POST HOLE PUNCH

Edwin Dahl, Denver, Colo.

Application February 21, 1938, Serial No. 191,596

5 Claims. (Cl. 255—1)

This invention relates to a post hole punch and has for its principal object the provision of a highly efficient, portable machine which will punch or drive a hole into the ground into which 5 a post such as a guard-rail post, fence post, or the like may be set.

This machine is not to be confused with pile drivers which drive a form into the ground by striking blows thereon, for in this machine the 10 entire hole forming element is continuously raised and dropped into the ground during the punching operation, no separate hole forming devices are employed. It has proven exceedingly valuable for setting guardrail posts on 15 mountain roads where the large quantity of rock makes digging an expensive proceeding.

Other objects of the invention are to provide a hole driver or punch which will break and crush any rock encountered in the hole; which 20 will be adjustable as to angle so that the hole will be vertical regardless of the incline of the surrounding terrain; which will require but a minimum of power; which can be attached to any ordinary road construction caterpillar tractor; and which may be easily and rapidly transported.

Other objects and advantages reside in the detail construction of the invention, which is 30 designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view illustrating the 40 device as it would appear in use.

Fig. 2 is an enlarged horizontal section taken on the line 2—2, Fig. 3.

Fig. 3 is a vertical section through the device.

Fig. 4 is a plan view of the invention with the 45 upper bracket broken away.

In the drawings a typical caterpillar tractor is indicated at 10. This invention is particularly designed to be applied to this type of tractor, although it is not limited to this particular use. Tractors of this type are provided with cable 50 winch drums such as shown at 31.

Tractors of this type are provided with a horizontal draw bar plate 11 supported upon projecting beams 12. The invention may be attached to the draw bar plate 11 or, if desired, may 55

be attached to a separate plate which in turn is attached to the draw bar plate 11.

The post hole punch comprises a vertical frame 13 hinged to a pair of angle feet 14 upon suitable hinge bolts 15. The frame 13 is supported in its 5 upright position by means of adjustable brace members 16. The brace members preferably comprise tubular sections for telescopically engaging rods 17 which are attached to the forward portion of the tractor in any desired manner. 10 These members are formed with a series of pin openings 18 by means of which the length of the entire brace member may be adjusted.

A V-shaped brace frame 19 is projected from the draw bar beams 12 to support a base plate 20. 15 The base plate 20 contains an opening for receiving a punch guide tube 21. The punch guide tube contains a series of projections or bosses 22 which are formed by welding a gob of iron thereon. The bosses 22 prevent the tube 21 from 20 slipping through the base plate 20, and provide a universal joint support for the tube 21, a pair of brace frames 23 and 24 extending from the frame 13 about the tube. In one of these frames, a pair of crank jack screws 25 is mounted which 25 act to clamp pads 26 against the tube 21. By tightening one of these screws and loosening the other, the vertical angle of the tube 21 may be varied.

The tube 21 is designed for guiding a heavy 30 solid iron punch 27, the lower extremity of which is pointed as shown at 28. The punch is raised in the tube through the medium of a cable 29 which returns over a pair of sheave wheels 30 to the cable drum 31 of the tractor. The sheave 35 wheels 30 are mounted in a swinging bracket 32 which in turn is suspended from a hinge bolt 33 at the top of the frame 13. The swinging of the bracket 32 accommodates the change in angle caused by lateral adjustment of the tube 21. 40

Operation

The operator drives the tractor to position the tube 21 over the desired place for the hole. He 45 then elevates the punch 27 to the top of the tube and releases the winch clutch of the tractor to allow the punch to drop. These punches weigh approximately three thousand pounds and upon release of the clutch, the punch falls guided by 50 the tube striking the ground to depress or punch a hole therein. The punch is elevated and dropped the number of times necessary to produce a hole of the desired depth. In ordinary ground, two drops of the punch produces a hole 55

approximately four feet deep. In rocky ground additional drops will be necessary.

For placing the guardrail holes along mountain highways, the incline of the highway would incline the tube, were no means provided for bringing it to vertical position. In this machine, however, if the operator desires to position his tractor transversely of the road, he adjusts the jack screws 25 to bring the tube 21 vertical when the tractor is setting on the incline of the road. Thereafter, all holes punched along the same gradient will be vertical without further adjustments. In some cases it is necessary that the tractor be placed longitudinally of the road. In these cases, the brace members 16 are adjusted so that the tube will be vertical as the tractor inclines.

It has been found advantageous to provide a small window or opening 34 in the tube by means 20 of which the operator can determine the depth of the hole. When the top of the punch appears opposite the window, the hole has reached the desired depth.

While a specific form of the improvement has 25 been described and illustrated herein, it is desired to be understood that the same may be varied, within the scope of the appended claims, without departing from the spirit of the invention.

Having thus described the invention, what is 30 claimed and desired secured by Letters Patent is:

1. A post hole punch attachment for tractors comprising: a vertical frame; means for attaching said frame to a tractor; a vertically positioned tube supported by said frame; a heavy pointed 35 punch member adapted to be dropped within said tube; and means for elevating said punch member within said tube.

2. A post hole punch attachment for tractors comprising: a vertical frame; means for attaching 40 said frame to a tractor; a vertically positioned tube supported by said frame; a heavy pointed punch member adapted to be dropped within said tube; means for elevating said punch member within said tube; and means for varying the vertical angle of said tube within said frame.

3. A post hole punch attachment for tractors comprising: a vertical frame; means for attaching said frame to a tractor; a vertically positioned tube supported by said frame; a heavy pointed punch member adapted to be dropped within said tube; means for elevating said punch member within said tube; means for varying the vertical angle of said tube within said frame; and means for varying the vertical angle of said frame on said tractor. 10

4. A post hole punch attachment for tractors comprising: a vertical frame; means for hinging the lower extremity of said frame to said tractor; brace arms supporting said frame from said tractor; a supporting member extending from said frame; a tube supported by said member; means for maintaining said tube vertical; an elongated, heavy, pointed punch member slidably mounted in said tube; a bracket extending over said tube; sheave wheels carried by said bracket; and a 20 cable extending from said punch member over said sheave wheels to the hoisting mechanism of said tractor so that said punch may be raised and dropped within said tube, so as to enter the ground when dropped. 25

5. A post hole punch attachment for tractors comprising: a vertical frame; means for hinging the lower extremity of said frame to said tractor; brace arms supporting said frame from said tractor; a supporting member extending from said frame; a tube supported by said member; means for maintaining said tube vertical; an elongated, heavy, pointed punch member slidably mounted in said tube; a bracket extending over said tube; sheave wheels carried by said bracket; and a 30 cable extending from said punch member over said sheave wheels to the hoisting mechanism of said tractor so that said punch may be raised and dropped within said tube, so as to enter the ground when dropped; and said bracket being hinged to said frame so that it may swing with the varying angles of said tube. 35
